UNITED STATES PATENT OFFICE.

ADOLPH L. DE LEEUW, OF CINCINNATI, OHIO, ASSIGNOR TO THE CINCINNATI MILLING MACHINE COMPANY, OF CINCINNATI, OHIO, A CORPORATION OF OHIO.

GRINDER STRUCTURE.

1,143,691.

Specification of Letters Patent. Patented June 22, 1915.

Application filed May 28, 1913. Serial No. 770,494.

To all whom it may concern:

Be it known that I, ADOLPH L. DE LEEUW, a citizen of the United States, and residing at Cincinnati, in the county of Hamilton and State of Ohio, have invented a new and Improved Grinder Structure, of which the following specification is a full disclosure.

This invention relates to mechanism for enabling work to be accurately tooled, and it is more especially concerned with that type of machine tools known as grinders, and it proposes certain structural characteristics promoting rigidity, as well as enhancing the facility with which the instrumentality may be manipulated.

One object within the contemplation of this invention is to devise a grinder in which a knee will be vertically adjustable on a grinding wheel column and which will in turn carry a saddle and overlying table, and in which the longitudinal movement of the table may be produced by the actuations of a lever horizontally extending from a bracket depending from the saddle in unitary relation therewith.

Another object is to render available a structure and various attachments therefor serving to promote the facility with which all sorts of grinding work may be accomplished especially for the purpose of accurately grinding gear cutters along radial planes, or grinding the peripheral tips of ordinary cutters at the proper clearance angle.

A further object is to create a rugged and structurally stiff machine applicable with especial advantage for the purpose of grinding work, and which will maintain all usual control features permitting the work to be brought into or out of contact with the grinder by the movement of one's legs and at the same time enabling the attendant to have the free use of both hands for controlling the position of the work in its holder or with relation to the tooth rest.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is an elevation partly in section showing features of this mechanism, together with details of the means for operating the table by the action of the legs leaving the hands free to manipulate the work. Fig. 2 is an end elevation partly in section showing further details of the grinding-wheel support, the reciprocating table, and the depending bracket or housing at the end of the saddle and at the side of the knee. Fig. 3 is a plan with the grinding head removed showing further relations of the parts. Fig. 4 is a detail showing the means for manually swiveling the table. Fig. 5 is a detail of the knee showing the arrangement of the shafts for elevating the same and for transversely sliding the saddle. Fig. 6 is a section through line 6-6 of Fig. 5 and showing the arrangement of the elevating shaft. Fig. 7 is a section through line 7-7 of Fig. 5 showing further details of the construction. Fig. 8 is a vertical axial section through the index or swivel head. Fig. 9 is a perspective of the machine.

Continuing now by way of a more detailed description, it will be noted that this organization comprises a standard or column A, the top of which carries the grinding wheel, and supported by this column are the parts that carry the work and enable it to be brought into any predetermined relation with the grinding wheel. In this instance the column A is cylindrical in form so as to permit of vertical as well as pivotal movements of the supported features, and retained on its upper end is the head B in which is journaled the spindle 1 of the grinding wheel. This head is preferably shaped and constructed in such a manner that it enables the tooth rest of my co-pending application Serial No. 770,170 filed May 27, 1913, to be secured to the same in various positions for producing spiral work and the like. Thus, at 2 and 3 are facets

having screw-threaded holes adapted to receive bolts to enable the tooth rest to be secured thereto. The particular construction of this head may of course be varied from 5 that shown in the drawings.

A knee C is vertically movable on the cylindrical shell 4 of the column A and it is prevented from turning with respect to the shell by means of a spline roller 5 (see Figs. 10 3 and 7) and its vertical elevation is secured by means of a rack 6 with which meshes a pinion 7 at the end of the shaft 8. This roller 5 is conical in form and it converges into a channel 50 cut into the periphery of the tubular sleeve 4 in parallelism with the axis thereof. This conical roller 5 is positioned by a pin 51 which is adjustably retained in the knee by the threads 52 and locked by means of the nut 20 53. This arrangement enables the conical roller 5 to be urged into the channel 50 until it accurately and without backlash interfits therewith. In this way the direction of reciprocation of the table may be preserved 25 in parallelism with the axis of the grinding wheel.

A worm wheel 9 actuated by a worm 11 on the end of the shaft 10 enables the hand wheel 12 to raise and lower the knee C. The 30 upper surface or table of the knee is provided with a horizontal guide way 13 extending radially with respect to the post or column.

Upon this knee C and slidably interfitting 35 with the guide way 13 thereof is a saddle D supporting certain features for enabling it to be moved toward and away from the column. This saddle provides a slide-way 14 extending transversely to the slide-way 40 13 on the saddle, and preferably it provides legs 15 and 16 which straddle the column and cover the slides of the knee. At one side, the saddle provides an overhanging part 17 from which depends a bracket 18 45 rigidly secured thereto by means of screws 19. At its lower end this bracket has clamped thereto a casing or gear box 20 which may be swung around and clamped in any desired fixed angular relation with 50 the depending bracket by means of the clamp screw 21. A pivot post 22 is provided by this box 20 and journaled thereon is a gear segment 23 which meshes with a pinion 24 at the end of a vertical shaft 25 which is 55 journaled in the bracket 18 and carries a gear 26 at its upper end engaging with a rack 27 whereby a table may be reciprocated. A lever 28 is secured to the gear segment 23 and extends horizontally and terminates in 60 an operating end 29 adapted to pass between the legs of the attendant so that by moving his knees he may cause the table to reciprocate.

The table E preferably comprises a lower 65 member 30 which slides in the transverse

guide provided by the saddle and to which is secured a rack 27. A supplementary portion or table proper 31 is pivoted at 32 to the lower member 30 and preferably is also supported at its ends by lugs 33 and 34 rising from the latter. This upper table portion 31 has one or more slides 35 which carry the index head and tail-stock that support the work. To enable the table portion 31 to be moved angularly on its lower supporting member, a hand operated worm shaft 36 is secured to the lower member and meshes with a worm wheel segment 37 secured to the upper member. 70 75

The head-stock F comprises a base 38 having alining lugs 39 and adapted to be secured in any desired longitudinal position on the table by means of bolts entering the slots in the latter. An angle block 40 is pivotally supported upon the base 38 and 80 provides an index point 40' adapted to co-operate with graduations 41 on the base so that it may be brought into any predetermined angular relation with said base. 85

At right angles to the plane of the supporting bearing face of the angle block 40 is a second face 42 upon which pivotally rests a head 43 in which is journaled a spindle 44 which supports the work on centers or by means of collet-chucks or otherwise. 90 This head 43 preferably provides seats 45 to which the universal tooth rest may be secured in the same manner as in the case of the head supporting the spindle of the grinding wheel. A pulley 46, by means of 100 a small screw projecting from its periphery into engagement with the spindle 44, may be caused to be locked to said spindle, but when it is desired to rotate work about a dead center, it may be released. Either on this pulley or on an integral portion of the spindle 44 are graduations 47 co-operating with a corresponding indicator line 48 on the head 43 so that the spindle or the work positioned by the pulley 46 may be rotated through a 110 definite angle. These graduations are preferably arranged on the pulley, however, since by means of suitable clamps or dogs 49 the work may be mounted on dead centers and turned through a definite angle without requiring rotation of the spindle 44. The office of this graduated spindle or actuating pulley is to serve as a means instrumental in greatly reducing the time and difficulty required for sharpening the peripheral 120 edges of the teeth of a cutter to secure the correct clearance angle. To accomplish this by the herein disclosed mechanism, it is exceedingly simple, since it is only necessary first to bring the radius line passing through a peripheral tip of one tooth into a position horizontally at right angles with the grinding surface of the wheel, then rotate the work exactly through the clearance angle required, which may be directly determined 125 130

by the graduations, then adjust the tooth rest on the table to maintain this position for each tooth in succession, and then feed the cutter in the usual manner in relation 5 with the grinding wheel. The correct grinding angle will then be secured.

Without further elaboration, the foregoing will so fully reveal the gist of this invention that others can by applying current knowledge readily adapt it for various applications without omitting certain features that, from the standpoint of the prior art, fairly constitute essential characteristics of the generic or specific aspects of this 15 invention, and therefore such adaptations should and are intended to be comprehended within the meaning and range of equivalency of the following claims.

Having thus revealed my invention, I 20 claim as new and desire to secure by Letters Patent of the United States:—

1. A machine of the nature disclosed combining a column, a knee vertically movable thereon and having a slide-way directed toward said column, a saddle vertically movable with said knee and horizontally slidable on said knee toward said column, and having a depending bracket vertically movable therewith, a table slidable on said 25 saddle transversely to said knee slide-way, a transmission extending from the lower end of said bracket adapted to actuate said table, and a horizontally movable lever pivotally supported at the lower end of said bracket and operative to impart motion to said table through said transmission.

2. A machine of the nature disclosed combining a column, a knee vertically movable thereon, a saddle vertically movable with 30 said knee and horizontally slidable on said knee and having a depending bracket vertically movable therewith, a table slidable on said saddle transversely to its movement on said knee, a shaft vertically extending from the lower end of said bracket into operative engagement with said table, and a horizontally swinging lever operatively connected with the lower end of said shaft to enable it to be actuated to reciprocate said 35 table.

3. A machine of the nature disclosed combining a column, a knee vertically movable thereon, a saddle vertically movable with 40 said knee and horizontally slidable on said knee and having a bracket vertically movable therewith depending at one side of said knee, a table transversely slidable on said saddle, a shaft vertically extending through said bracket and operatively connected with 45 said table, a gear fixed to the lower end of said shaft, and a horizontally extending

lever pivoted at one end to the lower end of said bracket and providing a gear segment meshing with said gear whereby upon horizontally swinging said lever the table will 50 be reciprocated.

4. A machine of the nature disclosed combining a column, a knee vertically movable thereon, an elongated bifurcated saddle vertically movable with said knee and horizontally 55 slideable on said knee and straddling said column, a bracket depending from one side of said saddle and movable as a unit therewith, an elongated table slideable on said saddle transversely thereto, a shaft vertically supported by said bracket and operatively connected at its upper end with said table, and lever mechanism supported by the lower end of said bracket and operative to rock said shaft.

5. A machine of the nature disclosed combining a cylindrical member providing in its periphery a channel extending in parallelism with the axis of said member, said channel having diverging side walls; a second member in close fitting relation with the periphery of said first member and movable axially relatively thereto; a conical roller carried by said second member and extending into said channel; and means for adjusting the roller radially to take up backlash between said two members.

6. A grinding machine of the nature revealed combining a post; a tubular sleeve concentric therewith; a knee having a portion circumscribing said sleeve; and means for splining said sleeve and knee together to permit axial movement but prevent rotary movement therebetween, said means being adjustable to take up wear and eliminate 95 backlash.

7. A machine of the nature disclosed combining a column; a knee vertically movable thereon and having a horizontal slide-way; a saddle guided by said slide-way and carried by said knee; a lever located lower than said saddle but mounted to be supported thereby; a table slidably mounted on the upper portion of said saddle; a transmission extending from said lever and operatively connected with said table; and adjustable means enabling said lever to be secured in different positions in its horizontal plane to enable said lever to be accommodated to different positions of an operator.

In witness whereof, I hereunto subscribe my name, as attested by the two subscribing witnesses.

ADOLPH L. DE LEEUW.
